Claims priority, application Canada May 7, 1969

Term of patent 14 years

Int. Cl. D9—99

U.S. Cl. D9—294

Des. 219,960

PAGE 2

FIG. 5

FIG. 6

FIG. 1 is a perspective view of a shirt collar support showing our new design;

FIG. 2 is an underside view of FIG. 1;

FIG. 3 is an embodiment of the shirt collar support of FIG. 1 showing our new design wherein the side wall is inwardly curved near the end wall;

FIG. 4 is an underside view of FIG. 3;

FIG. 5 is a further underside view of the shirt collar support shown in FIG. 1 but viewed from an angle different to the viewing of FIG. 2; and

FIG. 6 is a further underside view of the embodiment shown in FIG. 3 but viewed from an angle different to the viewing of FIG. 4.

We claim:

The ornamental design for a shirt collar support, as shown and described.
